Des. 224,904
Patented Oct. 10, 1972

224,904

WALL BRACE

Manuel J. Davis, Santa Cruz, and Carl A. Nelson, Glendale, Calif., assignors to M-J Metal Products, Inc.

Filed June 25, 1970, Ser. No. 23,664

Term of patent 14 years

Int. Cl. D8—08

U.S. Cl. D8—228

FIG. 1 is a plan view of a wall brace showing my new design;

FIG. 2 is a front elevation of FIG. 1; and

FIG. 3 is a view taken along lines 3—3 of FIG. 1.

We claim:

The ornamental design for a wall brace, substantially as shown.
